ELECTRIC DISCHARGE APPARATUS

Filed Nov. 8, 1928

Inventor:
Robert H. Dougherty,
by *Charles O'Ullor*
His Attorney.

UNITED STATES PATENT OFFICE

ROBERT H. DOUGHERTY, OF SCOTIA, NEW YORK, ASSIGNOR TO GENERAL ELECTRIC COMPANY, A CORPORATION OF NEW YORK

ELECTRIC DISCHARGE APPARATUS

Application filed November 8, 1928. Serial No. 318,040.

The invention relates to electric discharge apparatus, and more particularly to large-power, high voltage tubes employed for transmitting purposes.

5 Tubes of the transmitter type have heretofore been constructed in which the reentrant stem, through which the various leading-in conductors pass, is located in the neighborhood of the filament. However, it
10 has been found that devices constructed in this manner in many instances break due to the presence of one or more minute cracks or fissures developed in the stem which allow air leakage and destruction of the vacuum. While many theories may be advanced
15 to account for the development of these cracks, I believe that the phenomenon is the result of electrolysis which takes place about the stem under the action of the current
20 which flows through the conductors embedded in the stem. It has further been noted that the failure of the stem is particularly pronounced and accelerated in point of time when it receives an appreciable amount of
25 heat by radiation from the filament and other heated parts. While heretofore it has been proposed to remove the stem a distance away from the filament to prevent the deleterious effects referred to hereinbefore, the design of
30 tube produced with this purpose in view has also been subject to several disadvantages. In the first place, considerable difficulty has been experienced in the manufacture of the proposed tube, particularly in securing the
35 proper alignment of the various electrodes and leads which in an ordinary type of power tube may extend as far as 20 to 24 inches beyond the stem support and secondly, it has also been found that because of the length
40 and weight of the electrodes, large mechanical stresses are set up in the glass about the stem support. Moreover, the mechanical arrangement of the parts was such that the stem could not readily be positioned far enough
45 away from the filament, to present all objectionable heating effect on the glass. According to the present invention, I provide a novel form of tube construction in which the stem is located remote from the heated elec-
50 trodes but in which the disadvantages, re-

ferred to hereinbefore, are notably absent. In brief, the improved result is accomplished by building an inverted type of stem and by providing an extension or skirt portion which projects toward the filament and carries a support for rigidly aligning the filament conductors in their proper positions within the tube. This support also includes a heat barrier, for the purpose of preventing undue heating of the stem. 65

Some of the objects of my invention are: to provide an inverted stem in a vacuum tube which will be inexpensive and simple to fabricate but nevertheless will have a marked degree of practicability; to move the position of the stem and press member the maximum practicable distance away from the filament and other heated elements thereby maintaining the glass portions as cool as possible; to relieve mechanical stress in the stem 70 in the event the filament conductors are relatively long; to rigidly fix the position of the filament conductors and the filament supported therefrom, within the envelop and in general, to increase the operating life and 75 improve the design of electron discharge apparatus. Other objects and features will be apparent as the specification is perused in connection with the accompanying drawing in which Fig 1 represents an elevational 80 view, partly in section, of a power tube which embodies the features of my invention; Fig. 2 is an enlarged perspective view of a portion of the tube showing in detail, the improved stem and filament conductor support, 85 while Fig. 3 is an enlarged view of the support as seen in the direction of the arrows 3-3 in Fig. 1. 90

Referring to the drawing, numeral 1 designates the highly evacuated envelop of a representative high-power tube apparatus, the envelop being closed at the bottom by a cylindrical anode 2 in the manner well-understood in the art. Within the anode member, there is positioned a helical grid or control element 3 wound upon a suitable framework 4 and a V-shaped filament 5. The grid framework is supported from the envelop by means of a plurality of stay wires 6 which are equidistantly spaced about and secured to a grid 95 100

clamp 7 from which a flexible ribbon-shaped lead 8 is taken to a leading-in conductor 9 in the usual manner; this conductor passes through a transversely extending stem 10. 5 The lower end of the grid member 3 may be spaced concentrically within the interior of the cylindrical anode 2 by means of an insulating disk (not shown) which fits snugly within the cylinder 2, while the lower end of 10 the filamentary cathode 5 is carried by quartz or other insulating material secured to a centrally aligned support rod 11 fused into the inverted stem 12. The upper end of the envelop is closed by the combined stem and 15 press structure 12 which is of the inverted type and which is positioned as close as possible to said end of the envelop thereby to position this glass member the maximum distance away from the filament. The latter is 20 supplied with energy through conductors 13, 13 which are secured in the stem 12 and terminate in flexible leads 14, 14.

In high-voltage tubes it is necessary to make the inter-electrode leakage path as long 25 as possible and for this reason, among others, it is customary to separate as far as practicable, one from the other, the various electrodes and their supports. The long spacing of the charged members calls for relatively 30 long leading-in conductors, more especially for the filament, and in the prior attempts to furnish an inverted stem, it has been found that the conductors secured thereto produce large mechanical stress in this member. 35 When current is passed through the conductors, the stress may give rise to undue strain, this effect of course, being apart from the electrolytic phenomenon referred to hereinbefore. Moreover, the currents passing 40 through the conductors establish electromagnetic fields which may tend to bow or displace these conductors at places intermediate the points of support thereby tending to move the filamentary members out of their respective aligned positions. In order rigidly to fix 45 the position of each filament conductor, particularly the middle portion thereof, within the envelop, I provide a heat and electrically insulating disk 15 of glass, lava, isolantite, 50 quartz or the like which may be made of two semicircular plate members, for convenience in assembly. Extending through the thickness of the disk, there may be provided three apertures, one at the center and the others disposed diametrically opposite one another at 55 a distance corresponding to the space between the filament conductors. These apertures are of such size as snugly but slidably to fit about and receive the filament conductors 13, 13, 60 also the centrally disposed rod 11 in the manner shown in Fig. 3. The insulating disk 15 is carried by a screw clamp member 16 which is secured to an upper clamp 17 by means of a plurality of transversely extending arms 65 18, the upper clamp being somewhat similar

to the lower clamp. The disk 15 is provided with portions 19 which overhang the lower clamp member thereby the more securely to lock the disk within the clamp. The upper clamp 17 tightly embraces a cylindrical glass member 20 which is formed by tapering down a skirt or extension portion 21 constituted by continuing the reentrant cylinder 22 which carries the inverted stem 12. In the manufacture of a tube such as described, it has been found preferable to form the portions 21 and 22 out of separate pieces of tubing and then to join their ends by fusing together at a position determined, generally speaking, by the lower portion of the inverted stem member 12, as suggested by the line 23 (Fig. 1), instead of providing, at the outset, a single piece of tubing from which to form both of the glass portions. This mode of manufacturing procedure has the advantage in that the lower extension portion 21 may be fitted in a chuck and the taper 20 readily made without having attached thereto the added length of the adjacent reentrant portion 22. The grid clamp 7 tightly embraces the portion 21 and in order to prevent slippage, there may be provided a copper mesh between the clamp and the glass surface.

From the foregoing it is evident that the function of the double clamp arrangement 16, 17 is to provide a rigid support for the filament conductors at a position intermediate the stem 12 and the filament proper thereby rigidly fixing the special relation of these members and preventing undue strain at the stem. It is also evident that the disk 15, which forms part of the clamp arrangement, in addition to providing the support referred to, also serves to prevent the heat radiated from the filament from reaching the inverted stem. It is apparent that the design of the tube is marked with simplicity of manufacture and practicability, also as offering the greatest practicable spacing between the filament 5 and the stem thereby maintaining the latter as cool as possible under the effects of radiated heat. It has been found that a tube made in the manner described has a relatively long operating life which I believe to be due to the absence of cracks and fissures which normally would form in the prior stems under the action of electrolysis or other causes.

What I claim as new and desire to secure by Letters Patent of the United States, is:

1. In an electron discharge device, an evacuated envelop containing a plurality of co-operating electrodes, said envelop terminating in a hollow reentrant portion which is closed by an inverted stem, conductors for one of the electrodes passing through said stem, and means clamped about the exterior surface of said reentrant portion for supporting said conductors intermediate their length.
2. An electrode support comprising a plu-

rality of interconnected hollow clamp members, one of said members adapted to be secured to a portion of an envelop, a body of insulating material secured within the other 5 clamp member and adapted to support an electrode, said material having a portion which overhangs the clamp thereby the more rigidly to be secured thereto.

3. In an electron discharge device, an evacuated envelop containing a plurality of electrodes including a filament, said envelop terminating in an inverted stem, energy supply conductors for the filament secured to said stem and a clamp positioned intermediate the 10 length of said conductors for supporting the filament, said clamp comprising an insulating disk having apertures through which the conductors are threaded.

4. In an electron discharge device, an evacuated envelop containing a plurality of electrodes including an electrode which normally is heated, said envelop terminating in an inverted stem, energy supply conductors for the electrodes and a clamp positioned intermediate the length of said conductors for supporting the electrode which is heated, said clamp comprising an insulating disk in heat-shielding relation with respect to said stem. 25

5. In an electron discharge device, an evacuated envelope containing a plurality of cooperating electrodes, said envelope terminating in a hollow reentrant portion which is closed by an inverted stem, conductors for one of the electrodes passing through said 30 stem, and detachable means secured to the reentrant portion for supporting said conductors intermediate their length.

In witness whereof, I have hereunto set my hand this 7th day of November, 1928.

40 ROBERT H. DOUGHERTY.
